US0D1076608S

(12) **United States Design Patent** (10) **Patent No.:** **US D1,076,608 S**
(45) **Date of Patent:** **** May 27, 2025**

(54) **SILICONE SLEEVE FOR A TINNED CAN**

(71) Applicant: **Neil Aneja**, Roanoke, VA (US)

(72) Inventor: **Neil Aneja**, Roanoke, VA (US)

(**) Term: **15 Years**

(21) Appl. No.: **29/861,417**

(22) Filed: **Nov. 29, 2022**

Related U.S. Application Data

(63) Continuation of application No. 29/746,113, filed on Aug. 12, 2020, now Pat. No. Des. 973,448.

(57) **CLAIM**

The ornamental design for a silicone sleeve for a tinned can as shown and described.

DESCRIPTION

FIG. 1 is an isometric view of a silicone sleeve for a tinned can, showing my new design;

FIG. 2 is a right side view of the silicone sleeve for a tinned can, wherein left side, front and rear views are the same as the right side view of FIG. 2;

FIG. 3 is a top view of the silicone sleeve for a tinned can; and,

FIG. 4 is a bottom view of the silicone sleeve for a tinned can.

The broken lines depict portions of the silicone sleeve for a tinned can that form no part of the claimed design.

1 Claim, 3 Drawing Sheets
